WALL PAPER OR SIMILAR ARTICLE

Filed Sept. 2, 1931

INVENTOR

ALEXANDER MARTINEK

BY HIS ATTORNEY

Edward G. Miller

UNITED STATES PATENT OFFICE

ALEXANDER MARTINEK, OF WORCESTER, MASSACHUSETTS, ASSIGNOR TO PRAGER CO., INC., A CORPORATION OF NEW YORK

DESIGN FOR WALL PAPER OR SIMILAR ARTICLE

Application filed September 2, 1931. Serial No. 40,981. Term of patent 3½ years.

To all whom it may concern:

Be it known that ALEXANDER MARTINEK, a citizen of the United States, residing at Worcester, in the county of Worcester and State of Massachusetts, has invented a new, original, and ornamental Design for Wall Paper or Similar Article, of which the following is a specification.

In the accompanying drawing:—

The figure is a surface view of a piece of wall paper or similar article showing the design. The area within the dot and dash lines EF, FH, HG, and GE represent one complete unit of the design. Around this complete unit repeat units occur as shown on the

drawing. The area A, B, C, D represents a detail of a portion of the background of the design. The small area bounded by the corner of the drawing and the line JK illustrates the design with another portion of the background. The complete background consists of the background shown in the area bounded by the corner of the drawing and the line JK superimposed upon the background A, B, C and D.

I claim:

The ornamental design for wall paper or similar article as shown and described.

In testimony whereof I affix my signature.

ALEXANDER MARTINEK.
